GREGORY JOHN SPOHRER, OF EAST ORANGE, NEW JERSEY, ASSIGNOR OF ONE-HALF
TO CHARLES E. VAN VLECK, OF MONTCLAIR, NEW JERSEY.

INTERNAL-COMBUSTION ENGINE.

1,361,110.

Specification of Letters Patent.

Patented Dec. 7, 1920.

Application filed September 19, 1918. Serial No. 254,758.

To all whom it may concern:

Be it known that I, GREGORY J. SPOHRER, a citizen of the United States, residing at East Orange, in the county of Essex, State 5 of New Jersey, have invented certain new and useful Improvements in Internal-Combustion Engines; and I do hereby declare the following to be a full, clear, and exact description of the invention, such as will 10 enable others skilled in the art to which it appertains to make and use the same.

This invention relates to internal combustion engines and particularly to engines of this type designed for use in propelling 15 aircraft.

The design of internal combustion engines for aircraft has always presented a serious difficulty by reason of the varying atmospheric pressure at the different altitudes 20 in which the engine is operated. The reduction of the atmospheric pressure at altitudes at which aeroplanes are operated may reduce the compression pressure of the engine as much as 50% or more. If the engine be 25 designed to give the desired compression at a high altitude which is selected as the altitude at which the aeroplane will be operated normally, then the difficulty of running the engine when the aeroplane is on or near 30 the ground is greatly increased.

The present invention is directed to the provision of a novel construction for the propelling engine of an aeroplane including a means for effecting a regulation whereby 35 the engine may be run on the ground readily and also the desired compression may be obtained when the engine is operated at high altitudes. For this purpose provision is made for effecting an adjustment of the 40 size of the combustion chamber so that at whatever altitude the engine is being operated the size of this chamber may be so regulated as to produce the same degree of compression or such degree of compression 45 as may be desired. Various mechanical arrangements may be employed for so varying the volume of the compression chamber to compensate for variations in atmospheric pressure but that which I prefer to employ 50 involves the provision of means for shifting the engine shaft and the parts connected thereto in the direction of the axes of the cylinders of the engine. Such movement of the engine shaft results in moving the pis- 55 tons of the engine axially within their cyl-

inders so that the pistons reciprocate over a range which is changed as the engine shaft is moved. Thus, as the aeroplane propelled by the engine mounts to higher altitudes, the engine shaft may be moved by a suitable 60 manual controlling mechanism bodily toward the upper ends of the cylinders and the pistons are correspondingly moved within the cylinders. Therefore, when each piston is at the upper end of its compression 65 stroke it is closer to the upper end of the cylinder and the volume of the compression space is correspondingly reduced. In this way the same degree of compression is obtained at the end of the compression stroke 70 in each cylinder notwithstanding the fact that the air admitted to the cylinder during the inlet stroke was air at a reduced pressure.

I have illustrated in the accompanying drawings a construction which may be employed in practising the invention and this construction will now be described in detail but I wish it understood that the invention is not limited to the employment 75 of such a construction as that illustrated in the drawings as the principle of the invention may be employed in engines of widely different constructions. In these drawings, Figure 1 is an elevation of the engine broken away and sectioned in part; Fig. 2 is a transverse section of the engine; and Fig. 3 is an enlarged detail view of the indicator employed in connection with the manual controlling device. 85

Referring to these drawings, the engine is shown as having 4 cylinders arranged vertically in line though the number and arrangement of the cylinders may, of course, be varied as desired, the cylinders 1 having pistons 2 therein which are connected by connecting rods 5 to wrist-pins 4 on the crank shaft which is inclosed within the crank case 3. The compression chambers of the cylinders communicate with the usual intake manifold as indicated at 6, the inlet port 7 being controlled by valves 8 which are moved to and held in the closed positions by springs 9 acting on their stems. The valves 8 are operated by push-rods 10 which coact with cams 11 on the cam shaft 12.

The crank shaft 4 is not mounted in fixed bearings as is usual in internal combustion engines but instead is so mounted as to permit it to be moved bodily in a direction transverse to its axis, that is, in the direction

2
of the axes of the cylinders 1. The ends of the engine shaft may be mounted for rotation in bearing blocks 13 which are arranged to slide vertically in ways provided for their 5 reception upon the crank case 3. Each of these bearing blocks 13 is provided with a depending arm 14 which is arranged to coact with the adjusting means whereby the engine shaft is moved vertically. This adjusting means is shown as consisting of a shaft 15 mounted for rotation in bearings formed in the crank case 3 and coacting with the depending arms 14 of the bearing blocks and provided with means for turning the shaft 10 manually from a position convenient for the operator. The shaft 15 may have the portions thereof which coact with the arms 14 formed as eccentrics so that when the shaft 15 is turned the eccentrics would move the 15 arms 14 and the bearing blocks to which they are connected upwardly, the compression and expansion pressures being relied upon to hold the ends of arms 14 in coaction with the peripheries of the eccentrics. I prefer, 20 however, to provide for moving the arms 14 and the bearing blocks positively in both directions. For this purpose, the shaft 15 may have box cams 27 thereon, the grooves of which receive lateral projections 26 upon 25 the lower ends of the depending arms 14.

Any suitable mechanism may be provided for rotating the shaft 15 manually from a position convenient for the operator. In the drawings, one end of the shaft is shown 30 as extending through its bearing and provided with a worm wheel 16 meshing with a worm 17 on a short shaft 18 mounted in bearings carried by the crank case. On this shaft 18 is a gear 20 meshing with a worm 21 35 on a shaft 22 which extends through a tubular supporting member 19 up to a point convenient for the operator where it is provided with a hand wheel 23. This hand wheel is preferably provided with scale markings 25 40 and adjacent to it is an index 24.

Provision for bodily movement of the crank shaft as above described should not be allowed to disturb the proper relation of the cam shaft to the crank shaft. Therefore, 50 in the present instance the driving connection from the engine shaft to the cam shaft 12 is shown as including a telescopic connection which permits the cam shaft 12 to be mounted stationarily in its bearings while 55 being driven from the bodily movable engine shaft. One of the bearing blocks 13 is shown as provided with a lateral arm 31 carrying a short shaft 30 on which is a gear 29 meshing with a pinion 28 on the end of 60 the engine shaft. The shaft 30 also carries a bevel gear 32 meshing with a similar gear 33 on a short vertical shaft whose upper end carries a bevel gear 34 meshing with a bevel gear 35 on the cam shaft 12. This short vertical shaft consists of two telescopic sections 65

36 and 37, the latter of which is of polygonal cross-section and fits into a similar shaped axial opening in the member 36.

From the foregoing description it will be understood that when the engine is in operation the volume of the compression chambers at the upper ends of the cylinders may be regulated as desired. It is merely necessary for the operator to manipulate the wheel 23 and in doing so he may refer to the index 70 24 and the scale markings 25, as for instance by positioning the wheel 23 with reference to the readings of an instrument indicating altitude or atmospheric pressure. When the wheel 23 is moved the shaft 15 is turned and 80 the cams 27 thereon provided with eccentric cam grooves as is indicated in Fig. 2, operate to move the bearing blocks 13 and the engine shaft carried thereby broadly in the direction of the axes of the cylinders 1. This 85 moves the pistons 2 within their cylinders so as to vary the range of the reciprocation of the pistons and thereby vary the volume of the compression chambers so as to regulate the compression pressure as desired notwithstanding charges in the pressure of the air which is drawn into the cylinders during the inlet strokes. In so moving the engine shaft bodily the cam mechanism including the cam shaft 12 and the parts actuated thereby is in no way disturbed by reason of the telescopic connection between the parts 90 36 and 37 which maintains the driving connection to the cam shaft notwithstanding the movements of the engine shaft. 95

I claim:

1. An internal combustion engine comprising the combination of a cylinder, a piston therein, an engine shaft to which the piston is connected, a crank case, bearing blocks for the engine shaft movably mounted upon the crank case, arms extending from the bearing blocks, a regulating shaft mounted for rotation in bearings formed in the crank case and connected to said arms for moving the bearing blocks and the engine shaft carried thereby in a direction transverse to the length of the engine shaft, and a manual controlling member connected to the regulating shaft for turning it at will. 110

2. An internal combustion engine comprising the combination of a cylinder, a piston therein, an engine shaft to which the piston is connected, means for moving the engine shaft and the piston connected thereto bodily to vary the size of the compression chamber at the end of the cylinder, a cam shaft, a valve controlling a port of the cylinder and actuated by the cam shaft, and a driving connection from the engine shaft to 115 the cam shaft formed to compensate for the movements of the engine shaft relatively to the cam shaft.

3. An internal combustion engine comprising the combination of a cylinder, a 120

- piston therein, a crank case bearing blocks movably mounted upon the crank case, an engine shaft mounted for rotation in the bearing blocks and connected to the piston,
- 5 a regulating shaft mounted for rotation in bearings formed in the crank case and connected to the bearing blocks for moving them and the engine shaft carried thereby in a direction transverse to the length of the
- 10 engine shaft, a cam shaft mounted for rotation in bearings carried by the crank case, a valve controlling a port of the cylinder and operated by the cam shaft, and a driving connection from the engine shaft to the
- 15 cam shaft for rotating the cam shaft in correspondence with the rotation of the engine shaft, said driving connection being formed to compensate for movements of the engine shaft relatively to the cam shaft as the bearing blocks of the engine shaft are moved by 20 said regulating shaft.
4. In an internal combustion engine designed for use at low and high altitudes, a cylinder, a crank shaft, an intake valve, means for moving the crank shaft in the 25 direction of the axis of the cylinders whereby to vary the volume of the combustion chamber, and actuating means for said intake valve operatively connected to said crank shaft designed to open said valve a 30 substantially constant amount, in whatever adjusted position the crank shaft may be.

In testimony whereof I affix my signature.

GREGORY JOHN SPOHRER.
